F. LIST.

MERCHANDISE DISPLAY BOX.

APPLICATION FILED FEB. 6, 1920.

1,378,363.

Patented May 17, 1921.

UNITED STATES PATENT OFFICE.

FRANZ LIST, OF NEW YORK, N. Y., ASSIGNOR TO CHARLES A. BLADES, OF ARLINGTON,
NEW JERSEY.

MERCHANDISE-DISPLAY BOX.

1,378,363.

Specification of Letters Patent. Patented May 17, 1921.

Application filed February 6, 1920. Serial No. 356,621.

To all whom it may concern:

Be it known that I, FRANZ List, a citizen of the United States, and a resident of Bronx, New York city, in the county of Bronx and State of New York, have invented certain new and useful Improvements in Merchandise-Display Boxes, of which the following is a specification.

The invention has particular reference to boxes for holding merchandise for display on store counters, glass cases set thereon and the like, and involves certain improvements hereinafter pointed out on the display box made the subject of Letters Patent No. 15 1,247,848 granted to me on November 27, 1917.

The box of my invention comprises a body or holding portion in which the goods are placed, a hinged cover portion which may 20 close over said body portion and also be turned into vertical position and used as a prop to support said body portion in an open inclined position to display its contents, and means for maintaining said body 25 and cover portions in their correct relative position when the box is in its open display position and resting on a counter or other smooth surface, said means preferably comprising a plurality of hinged bracket or 30 feet members slit from the material of the cover and adapted when the cover is turned to vertical position for supporting the body portion in an inclined display position, to be turned under said body portion and coöperate with the then lower end of the cover to 35 firmly support said body portion.

One difficulty which has been found to exist in the use of display boxes of the character to which my invention pertains, is 40 that when the box is in display position an accidental push on the lower end of the box, as when examining the merchandise, frequently results in the cover being turned down rearwardly of the body portion so 45 that the whole box becomes more or less flattened or straightened out and unpresentable. The result just described is particularly liable to occur when the box is set on a smooth counter or glass case or other 50 surface on which it may readily slide when accidentally pushed or even purposely moved. One of the main objects of my invention is to provide a display box of the character in question which without increase of material or substantial if any in-

crease in cost of production, will possess means to prevent the collapsing of the box when jarred or moved while resting on a smooth surface, and this object I accomplish by the provision of the bracket or feet 60 members hereinbefore referred to and which also possesses the further advantage of relieving the cover, then acting as a prop, from being compelled to support the entire weight of the higher end of the body of the 65 box and its contents.

The invention will be fully understood from the detailed description hereinafter presented, reference being had to the accompanying drawings, in which:

Fig. 1 is a perspective view of a display box, shown in open position, embodying my invention;

Fig. 2 is a like view of the box taken from the rear thereof;

Fig. 3 is a central vertical longitudinal section through the same;

Fig. 4 is a top view of the box, with its parts shown in closed position;

Fig. 5 is a side view of the same;

Fig. 6 is a vertical section, partly broken away, through a portion of the same taken on the dotted line 6—6 of Fig. 5, and

Fig. 7 is a top view of a modified construction of box embodying my invention, 85 the modification residing in the fact that the cover is formed with only one bracket or foot member instead of the two bracket or feet members shown in Fig. 4.

In the drawings 10 designates the body 90 portion of the box and 11 the cover therefor. The body portion 10 is of rectangular outline and has a bottom 12, ends 13 and sides 14.

The cover 11 has a top 15 which is coextensive, or substantially so, with the body 10, a rear end 16 to match against the rear end of said body and short sides 17 adapted to lie close against the exterior surfaces of the sides 14 of said body.

The opposite sides of the body 10 are provided with fixed trunnions 18, these trunnions being on the rear portions of said sides and preferably near the middle of the height of the same.

The sides 17 of the cover 11 are formed with longitudinal slots 19, whose front ends merge on curved lines into substantially right angular slots 20 which afford seats 21 for the trunnions 18 when the parts of the 110

box are in their display relation shown in Figs. 1, 2 and 3. The slots 19 permit the cover 11 to be slid rearwardly over the body 10, or rearwardly from the position of 5 said cover shown in Fig. 5, and then turned upwardly into vertical position with the end 16 resting on a suitable support 22, as shown in Fig. 3; and when the cover 11 is thus turned into vertical position the trunnions 10 18, either by a movement given to the cover or said body or both, are carried into the slots 20 and find seats 21 therein, whereby said cover is enabled to support the body 10 in the inclined position in which the body is 15 shown in Figs. 1 and 3, in which position said body may properly display the merchandise that may be placed therein, while at the same time the then front face of the cover may effectually expose any advertisement or other matter that may be borne 20 thereby.

The box, as far as the details thereof have been specifically referred to by reference numerals, while desirable in many respects 25 has developed certain difficulties in practical use and particularly when made to hold merchandise of substantial weight and placed on smooth counters or other surfaces, and one of these difficulties has been that the 30 end 16 of the cover being of limited surface area has permitted the cover to fold or turn rearwardly on sometimes even slight rearward pressure being applied to the body 10.

My invention provides means for preventing the turning backwardly of the cover 11 under the conditions just explained, and said means, in the preferred construction, reside in the bracket or feet 23, 24 slit on three edges from the top 15 of the cover 11 40 and left integral at their outer edge 25, along scored or weakened lines, with said top, whereby said brackets or feet become in effect hinged to said top and may be turned forwardly in opposite directions 45 therefrom and be made to extend at right angles to said top and below the rear elevated portion of the body 10, as shown in Figs. 1, 2 and 3. The forward edges of the brackets or feet 23, 24 are inclined inwardly 50 and rearwardly, as at 26, so that when said brackets or feet are extended below the inclined body 10, said edges, then representing the upper ends of said brackets or feet, may be engaged by and afford rests for the upper inclined end portion of said body and take the weight of the merchandise therein, as shown in Fig. 3. The brackets or feet 23, 24, when in use, project forwardly of the end 16 of the cover 11 and afford extended 60 supports for the body 10, and said supports by taking the weight of the body 10 overcome any tendency of the cover 11 to fold backwardly and permit me to utilize the weight of the body 10 for maintaining the 65 cover in vertical position. It will be seen

that any pressure tending to so slide the box as to turn the cover backwardly, will be resisted by the weight of the box on the upper ends of the brackets or feet 23, 24, which would have to lift the rear end of the box 70 before the cover could fold backwardly. The lower edges of the brackets or feet 23, 24 are of such length that they resist any tendency of the cover 11 to be accidentally turned forwardly. The brackets or feet 23, 75 24 thus not only permit rather heavy merchandise to be displayed in the box but resist any tendency of the cover to be accidentally collapsed either backwardly or forwardly under ordinary circumstances. 80

I prefer to supply the cover of the box with two bracket or feet members 23, 24 but in many instances the provision of one bracket or foot member will be sufficient to carry out the purposes of my invention, and 85 hence in Fig. 7, I show a box whose cover has only one foot member, numbered 30, whose construction and operation will be understood without further extended description, since the foot 30 performs the same duties 90 as either or both of the feet 23, 24.

I do not limit my invention to all the details of form and construction described, since these may be varied within the scope of the appended claims. For illustration, 95 the trunnions 18 could be secured to the sides 17 of the cover and the slots 19 formed in the sides 14 of the body 10, this being a reversal of location of parts but possessing the disadvantage that the trunnions would in 100 adjusting the cover be caused to slide against the contents of the body 10. I however include such construction within the scope of my invention.

What I claim as my invention and desire 105 to secure by Letters Patent, is—

1. A merchandise display box of the character described, comprising a body portion for holding the merchandise, and a cover therefor in sliding and hinged relation thereto and adapted to be turned vertically 110 to serve as a prop for holding the body portion in inclined display position, said cover having bracket or feet members slit therein, adapted when the cover is turned vertically 115 to be folded forwardly in opposite directions beneath and close to the elevated rear portion of said body, and said feet members being disposed inwardly from the side edges of said cover and at their free ends 120 being when in initial position closely adjacent to each other along the longitudinal central line of said cover.

2. A merchandise display box of the character described, comprising a body portion for holding the merchandise, and a cover therefor in sliding and hinged relation thereto and adapted to be turned vertically 125 to serve as a prop for holding the body portion in inclined display position, said cover 130

- having a bracket or foot member slit therein adapted when the cover is turned vertically to be folded forwardly under the elevated rear portion of said body close to the bottom thereof, and said cover having corresponding longitudinal slots in its sides and said body having trunnions engaged in said slots, whereby the cover is permitted to slide on said body and also becomes hinged thereto.
- 10 3. A merchandise display box of the character described, comprising a body portion for holding the merchandise, a cover therefor in sliding and hinged relation thereto, and a bracket or foot member carried by
- 15 said cover, said cover being adapted to be

turned into vertical position, said body to be moved into inclined position and said bracket or foot member to be turned forwardly below the upper end of said body to support the same and its contents, and said cover having corresponding slots in its sides and said body having trunnions engaged in said slots, whereby the cover is permitted to slide on said body and also becomes hinged thereto.

Signed at New York city, in the county of New York and State of New York, this 3rd day of February A. D. 1920.

FRANZ LIST.
